UNITED STATES PATENT OFFICE.

EDWARD W. GROGAN, OF AMARILLO, TEXAS.

PUMP JACK.

Application filed March 12, 1923. Serial No. 624,647.

To all whom it may concern:

Be it known that I, EDWARD W. GROGAN, a citizen of the United States, residing at Amarillo, in the county of Potter and State 5 of Texas, have invented certain new and useful Improvements in Pump Jacks, of which the following is a specification.

The object of my invention is to provide an inexpensive, convenient and durable 10 pump jack which may be operated upon deep well pumps without requiring a heavy driving force. The invention is applicable to oil wells and also to pumps operated by windmills or by an engine and may be adjusted 15 so as to be operated by hand when the windmill or engine is being repaired. The invention is illustrated in the accompanying drawings and consists in certain novel features which will be hereinafter fully set 20 forth.

In the drawings:

Figure 1 is a side elevation of my improved jack showing it arranged for use in connection with a deep well oil pump;

Fig. 2 is a similar view showing the device arranged to be operated by a windmill;

Fig. 3 is an enlarged detail section on the line 3—3 of Fig. 2, and

Fig. 4 is an enlarged detail section of one 30 of the bearings or connections between the supporting frame and one of the levers.

In carrying out my invention, I employ a platform 1 which may be of any convenient or preferred construction and upon the said 35 platform I erect a rigid frame 2 consisting of upwardly converging standards connected by a brace 3 at their upper ends. The standards are composed of duplicate members and the brace 3 is arranged between the members 40 of the standards, as will be readily understood. Extending between the members of each standard and fulcrumed upon one standard is a lower lever 4 which carries at its forward end a hanger 5, said hanger supporting a clamp 6 which is secured to the 45 pump rod 7 so that the oscillation of the lever will effect a vertical reciprocation of the clamp and of the pump rod and thereby raise liquid from the well. The upper end 50 of the hanger seats in a recess in the upper edge of the lever and is held therein by a strap 8, as will be readily understood on reference to Figs. 1 and 2. The clamp 6 consists of a body 9 through which the lower 55 ends of the hanger fit tightly, nuts 10 being

fitted on the ends of the hanger below the body to prevent withdrawal of the hanger. Spaced ears 11 project from the ends of the body and a lever 12 is pivoted between the ears of one set while between the ears of the other set is pivoted a latch bolt 13 adapted to pass through the forked end 40 of the lever, a nut 41 being mounted on the end of the bolt to be turned home against the lever and hold it to the body of the clamp. 60 In the face of the body opposed to the lever is a notch 42 and a removable jaw 43 is fitted over each wall of said notch and over the opposed face of the lever whereby, when the lever is locked to the body, the pump rod 70 disposed between said jaws will be securely clamped and consequently caused to follow the movements of the hanger. If the jaws be removed, the lever and body may be clamped about a pump casing, or other 75 member, when the withdrawal of the same from the well is necessary or desirable. In such event, the hanger is removed from the lever 4 and connected to a block and tackle or other lifting mechanism. 80

The lever 4 is pivoted upon the frame 2 by a fulcrum bolt 14 inserted through the frame standard and through any one of a series of eyes or loops 15 on the lever whereby the stroke of the lever may be regulated. 85 Above the lever 4 is a lever 17 which is fulcrumed upon the other standard of the frame by a fulcrum bolt 18 inserted through the said standard and one of the eyes or loops 19 on the lever. The rear ends of the 90 levers 4 and 17 are provided with longitudinal series of openings 21 and a link 22 serves to connect the said rear ends of the levers, the ends of the link being attached to the respective levers by pivot bolts 23 inserted 95 through the ends of the link and through the proper openings 21, as will be readily understood.

In the arrangement shown in Fig. 1, a pitman 24 is adjustably pivoted at its upper 100 end to the front end of the upper lever 17, and this pitman consists of similar straps receiving the end of the said lever between them and having their lower ends pivoted to the front end of an arm 25 projecting 105 forwardly from and secured to a vertically disposed rocking arm or lever 26 which is fulcrumed upon brackets or rails 27 secured upon the base or platform 1. A spacer block 28 is secured between the members of the pit- 110

man 24 between the levers 4 and 17 so that binding of the pitman members against either lever will be prevented. Movable connected with the upper end of the rocking arm or lever 26 is a driving rod 29 which may be connected at its rear end with any convenient operating mechanism, as a pulley 30 driven from a distant motor. The arrangement shown in Fig. 1 is especially adapted for use in connection with oil wells, as will be readily understood. When the device is to be operated by a windmill, the pitman 24 and the operating lever 26 with the parts co-operating therewith are removed and the driving rod 31 from the windmill is pivotally attached at its lower end to the front end of the upper lever 17, as shown in Fig. 2.

Around the fulcrum bolts 14 and 18, I provide a plurality of anti-friction rollers 32 and the eye 15 or 19, as the case may be, is large enough to accommodate the said rollers so that frictional resistance will be minimized and the levers may oscillate freely and easily.

It will be readily understood that the vertical reciprocation of the windmill rod 31 will cause the lever 17 to oscillate about its fulcrum, and this oscillation will be transmitted through the coupling link 22 to the lever 4 which, in turn, will effect vertical reciprocation of the clamp 6 and the pump rod 7 to which it is secured. When the device is to be operated by an engine or with an ordinary oil well rig as in Fig. 1, the power is applied through the driving rod 29 so as to oscillate the lever 26 and this oscillation will be transmitted through the arm 25 and the pitman 24 to the lever 17, as will be readily understood. From the lever 17, the power will be transmitted to the pump rod in the manner previously stated. If, for any reason, the windmill or the engine cannot be utilized as a source of power, the coupling link 22 may be detached from the lower lever 4 and said lever then oscillated by hand so as to raise liquid through the pump.

It will be readily noted that I have provided a very simple and compact mechanism and the power applied to the same

will be very advantageously utilized inasmuch as the levers 4 and 17 will operate with very little resistance and will apply the force to the pump rod in such a manner that a very slight expenditure of energy will effectually operate the pump. The stroke of the levers may be adjusted within a considerable range by shifting the fulcrum bolts and the coupling link 22 so that the pump may be operated positively and easily even when the windmill is exposed to only a very light breeze or when the engine connected with the jack is very small and of low horse power. It is to be understood that the device is intended particularly for operating deep well pumps, the oil or water being carried through a discharge pipe 45 to a tank or reservoir.

Having thus described the invention, what is claimed as new is:

1. A pump jack comprising standards connected at their upper ends, an upper lever fulcrumed upon the rear standard, a second lever fulcrumed upon the front standard below the first lever, means carried by the front end of the second lever to secure a pump rod, a coupling link adjustably connecting the rear ends of the two levers, and means for applying power to the front end of the upper lever.

2. A pump jack comprising a supporting frame, an upstanding lever mounted for rocking movement on the base of the frame, means for applying power to the upper end of said lever, an arm projecting forwardly from said lever, a lever adjustably fulcrumed upon the frame near the upper end thereof, a pitman connecting the front end of said lever with the front end of said arm, a third lever fulcrumed upon the frame below the second-mentioned lever and in a vertical plane in advance of the vertical plane of the fulcrum of said second-mentioned lever, a pump rod clamp carried by the front end of the third lever, and a coupling link connecting the rear ends of the second and third levers.

In testimony whereof I affix my signature.
EDWARD W. GROGAN. [L.S.]
